UNITED STATES PATENT OFFICE.

LEON F. HOFFMAN, OF FRANKLIN, PENNSYLVANIA, ASSIGNOR TO CHICAGO PNEUMATIC TOOL COMPANY, OF NEW YORK, N. Y., A CORPORATION OF NEW JERSEY.

CYLINDER HEAD FOR INTERNAL-COMBUSTION ENGINES.

Application filed June 10, 1924. Serial No. 719,054.

To all whom it may concern:

Be it known that I, LEON F. HOFFMAN, a citizen of the United States of America, and resident of Franklin, in the county of Venango and State of Pennsylvania, have invented new and useful Improvements in Cylinder Heads for Internal-Combustion Engines, of which the following is a specification.

10 This invention relates to internal combustion engines utilizing as fuel the heavier hydro-carbon oils such as crude petroleum and its heavier refined and semi-refined products. More particularly it concerns an improved type of head for such an engine.

15 The cylinder head of an engine of the type described as ordinarily constructed comprises a large casting, cored for the water cooling system, forming a closure for the cylinder and also providing a combustion chamber separated from the cylinder by a perforated water cooled partition. A relatively small cap closes the combustion chamber and is secured to the head. Thus the ordinary head consists primarily of one large mass of cast metal with cored walls and a cored partition plate which in service is subjected to the intense heat produced in the combustion chamber, which heat has its greatest effect upon the integral water-cooled division or partition plate perforated for the passage of the exploding charge from the combustion chamber to the cylinder. In service this head has a tendency to fail through the development of cracks generally in or around the division plate. These failures are probably due to casting strains set up when the heads are made or to the localization of the intense heat produced in the combustion chamber or to both. The failure of heads of this type is relatively high and frequently forms a considerable portion of the repair and upkeep expense of an oil engine.

45 Among the objects of the invention are to reduce greatly or to avoid entirely the fracture of cylinder heads and the expense occasioned thereby or incident thereto, to cheapen the cost of manufacture of cylinder heads and to reduce the percentage of defective and rejected heads, to facilitate the repair of oil engines with a consequent reduction in time lost and in repair cost, and in general to improve prior devices of the class described and to prevent waste.

The invention comprises the construction of the cylinder head in three parts instead of two, namely a cylinder head ring, a separator or partition member and an explosive chamber member. By this construction the mass of metal forming any one casting is greatly reduced and the liability of defective parts resulting from casting strains is correspondingly minimized. When the parts are bolted together and to the cylinder there is provision for slight relative expansion particularly of the combustion chamber member and of the partition member, the decreased mass of these parts as compared with prior construction permitting quick distribution of heat therethrough and largely eliminating the stress and strain which would result were they integrally united.

20 The invention is illustrated in the accompanying drawings, in which:

25 Fig. 1 is a perspective view of the cylinder end of an oil engine embodying the present invention;

30 Fig. 2 is a vertical sectional view on an enlarged scale through the cylinder head and the adjacent end of the cylinder;

35 Fig. 3 is an end elevational view of the parts shown in Fig. 2 on a slightly reduced scale; and

40 Figs. 4, 5 and 6 disclose the parts of the cylinder head, namely the cylinder head ring, the partition member and the combustion chamber member respectively in top plan, section, and bottom plan.

45 A typical installation of the invention is disclosed in Fig. 1 wherein A is the foundation for an oil engine, B its cylinder, C the exhaust conduit, D the cylinder head assembly, E a water connection for the water jacket of the engine, and F the fuel pipe, these parts with the exception of the cylinder head assembly D being of the usual construction.

50 The cylinder head assembly comprising the present invention consists of a cylinder head ring 7, a partition member 8 and a combustion chamber member 9. The cylinder head ring 7 (clearly disclosed as a separate element in Fig. 4) engages the end of the cylinder and is secured thereto by any suitable means such as cap screws 10 which extend through suitable bores 11. Member 7 only partly closes the end of the cylinder since it has a central opening 12 of smaller diameter than the cylinder bore. The parti-

tion member 8, disclosed as a separate element in Fig. 5, is adapted to be applied to and to be secured to member 7 in assembling the cylinder head. A projecting boss 13 on partition member 8 extends into and through bore 12 of member 7 with a loose fit. This boss, as shown in the sectional views of Fig. 2 and Fig. 5, is of substantial thickness and is cooled by a water chamber 14 extending therethrough. One or more (in the present instance two) openings 15 extend entirely through member 8 and its boss 13 for the passage of the exploding charge from the combustion chamber to the cylinder chamber of the engine. The combustion chamber member 9, disclosed as a separate element in Fig. 6, has a flange 16 which engages the upper surface of partition member 8 and suitable means such as cap screws 17 extend through openings 18 in flange 16 of member 9 through registering opening 19 in member 8 and into threaded sockets 20 in member 7 to securely unite members 9 and 8 in assembled relation upon cylinder ring member 7.

When the parts are assembled, as illustrated in Fig. 2, it will be seen that water passages 21 in member 7 connect with water passages 22 in member 8 and these in turn with the water passages 23 in member 9. To prevent leakage a gasket 24 of copper or other suitable material is interposed between the abutting faces of members 8 and 7 and a similar gasket 25 is interposed between the abutting faces of members 9 and 8 in addition to the usual gasket 26 between the end of the cylinder and the head. In addition to the opening 27 for the fuel pipe F, the combustion chamber member 9 may be provided with such other openings as are necessary or desirable in an engine of this kind, including an opening 28 for the hot tube device 29 protected by casing 30 and used for starting purposes, also an opening 31 for the admission of compressed air also for starting purposes.

From the above it will be apparent that the construction of the cylinder head in three parts reduces the mass of metal in each part and the liability of defective parts through casting strains, that the reduced mass of the parts results in more rapid and even distribution of heat therethrough, that the manner of assembling the parts permits relative movement of the same under expansion, that the loose fit of boss 13 of the partition member 8 in the opening of the cylinder ring member 7 relieves the latter of any stress due to the more rapid expansion of the partition member resulting from the intense heat of the exploding gases as they pass through the bores or perforations 15, and that in the event of a defect or breakage of any one of these members its replacement with a new part is readily

made and the expense is greatly reduced since it is unnecessary to discard the entire cylinder head.

I claim as my invention:

1. In an oil engine, in combination with the cylinder thereof, a three part cylinder head comprising a cylinder head ring engaging the cylinder and providing an opening of smaller diameter than the cylinder bore, a perforated partition member engaging said ring and closing said opening, and a combustion chamber member engaging said partition member, and means securing the parts of the head together and to said cylinder. 75

2. In an oil engine, in combination with the cylinder thereof, a three part cylinder head comprising a cylinder head ring engaging the cylinder and providing an opening of smaller diameter than the cylinder bore, a partition member engaging said ring and having a perforated boss extending into said opening, and a combustion chamber member engaging said partition member, and means securing the parts of the head together and to said cylinder. 85

3. In an oil engine, in combination with the cylinder thereof, a three part cylinder head comprising a cylinder head ring engaging the cylinder and providing an opening of smaller diameter than the cylinder bore, a partition member engaging said ring and having a boss extending into and substantially filling said opening, and a combustion chamber member engaging said partition member, said boss having at least one opening therethrough to provide restricted communication between the cylinder bore and the combustion chamber, and means securing the head parts together and to said cylinder and sealing the joints therebetween. 100

4. In an oil engine, in combination with the cylinder thereof, a three part cylinder head comprising a cylinder head ring engaging the cylinder and providing an opening of smaller diameter than the cylinder bore, a partition member engaging said ring and having a boss extending into and through said opening, said boss being cored for the circulation of cooling fluid, and a combustion chamber member engaging said partition member, said boss having at least one opening therethrough to provide restricted communication between the cylinder bore and the combustion chamber, and means securing the head parts together and to said cylinder and sealing the joints therebetween. 115

5. The combination with a water cooled oil engine of a three part cylinder head comprising a cylinder head ring engaging the cylinder, a perforated separator or partition member engaging said ring and reducing the opening provided by the latter, and a com- 125

bustion chamber member engaging said partition member, means securing the parts of the head together and to said cylinder, said combustion chamber member having cored 5 walls and the other parts having perforations for the passage of cooling water from the cylinder to said walls.

6. In a water cooled oil engine, in combination with the cylinder thereof, a three 10 part head comprising a cylinder head ring engaging the cylinder, a partition member engaging said ring and having a cored boss extending into the said opening of said ring, said ring providing perforations for 15 the passage of cooling water from the cylinder to said cored boss, and a combustion chamber member engaging said partition member, and means securing the parts of the head together and to the cylinder.

20 7. In a water cooled oil engine, in combination with the cylinder thereof, a three part head comprising a cylinder head ring engaging the cylinder and providing an opening of smaller diameter than the cylinder bore, a partition member engaging said ring and having a cored boss extending into 25 said opening, said ring providing perforations for the passage of cooling water from the cylinder to said cored boss, and a cored 30 combustion chamber member engaging said partition member, said partition member having at least one opening therethrough providing connection between the combustion chamber and the cylinder bore, said 35 ring and said partition member having passages providing access of the cooling water to the cored walls of said combustion chamber member, and means securing the parts of the head together and to the cylinder.

40 8. A three part head for internal combustion engines comprising a cylinder head ring adapted to engage the cylinder, a combustion chamber member, and a water-cooled partition member interposed between said 45 two first named members and reducing the opening provided by said ring.

9. A three part head for oil engines and the like comprising a cylinder head ring

adapted to engage the cylinder, a combustion chamber member, and a partition member arranged to be interposed between said two first named members, said partition member having a water-cooled portion fitting into and reducing the opening in said ring. 50 55

10. A three part head for internal combustion engines comprising a cylinder head ring adapted to engage the cylinder, a combustion chamber member, and a partition member arranged to be interposed between said two first named members, said partition member having a boss projecting into and through the end opening of said ring and having at least one opening for providing restricted connection between the combustion 60 65 chamber and the bore of the engine cylinder.

11. A three part head for internal combustion engines comprising a cylinder head ring adapted to engage the cylinder, a combustion chamber member, and a partition member arranged to be interposed between said two first named members, said partition member having a boss arranged to extend through and substantially fill the end opening of said 70 75 ring, said boss being cored for the passage of cooling fluid therethrough and having at least one opening for establishing restricted connection between the combustion chamber and the bore of the engine cylinder.

12. A three part head for hydrocarbon engines comprising a cylinder head ring adapted to engage the cylinder, a cored combustion chamber member, and a partition member arranged to be interposed between said two first named members, said partition member having a cored boss extending into the open end of said ring and having at least one restricted opening therethrough not connected to its cored interior, said ring 80 85 providing passages for the circulation of cooling fluid from the engine through the cored parts of said two last named members.

Signed by me at Franklin, Pennsylvania, this 6th day of June, 1924.

LEON F. HOFFMAN.
